Lansing P. Shield, Ridgewood, N. J., assignor to
The Grand Union Company, New York, N. Y.,
a corporation of Delaware

Application November 10, 1948, Serial No. 149,569

Term of patent 14 years

(Cl. D33—3)

To all whom it may concern:

Be it known that I, Lansing P. Shield, a citizen of the United States, residing in Ridgewood, in the county of Bergen, State of New Jersey, have invented a new, original, and ornamental Design for a Support and End Member for Shelves, of which the following is a specification, reference being had to the accompanying figures of the drawing, forming part thereof.

Fig. 1 is a perspective view of a support and end member for shelves embodying my design, the stop being shown as seen from the front;

Fig. 2 is a perspective view of a support and end member for shelves embodying my design, the stop being shown as seen from the rear;

Fig. 3 is a top plan view of the construction shown in Figs. 1 and 2;

Fig. 4 is a side elevation of the construction shown in Figs. 1 and 2;

Fig. 5 is a front elevation of the construction shown in Figs. 1 and 2; and

Fig. 6 is a view of the construction shown in Figs. 1 and 2 as seen from the bottom.

I claim:

The ornamental design for a support and end member for shelves, as shown.

LANSING P. SHIELD.
